MULTIPLE TYPE VACUUM CUPS

Horace V. Farmer, Sault Ste. Marie, Ontario,
Canada

Application October 15, 1943, Serial No. 506,434

1 Claim. (Cl. 248—206)

This invention relates to holding devices and more particularly to a multiple action holding device whereby the device may be attached to a structure by the means employed and also whereby an object or objects may be held to the vacuum cup in the same manner.

The principle object of the invention is to provide a holder of the class described which is formed integrally and does not require supplementary holding members such as hooks, studs and bolts and the like embedded in the cup of conventional design.

A further object of the invention is a multiple type vacuum cup holder provided with a means of expelling the air equally from each opposite cup.

Still other objects of the invention are to provide a multiple holder type of vacuum cup, to provide an inexpensive holder manufactured integral and to generally provide an improvement in the art.

With the above noted and other objects in view which may appear as the description proceeds the invention resides in the novel construction and arrangement of cooperating parts as hereinafter more specifically set forth, claimed and shown in the accompanying drawing forming part of this application and in which:

Fig. 1 is a longitudinal sectional view of my invention,

Fig. 2 is an end elevational view of the same, and

Fig. 3 is a view similar to Fig. 2 showing a slight modification of the invention.

Referring more in detail to the drawing in which similar reference characters designate corresponding parts throughout the several views it will be seen that the invention resides in a homogeneous mould such as illustrated in Figs. 1 to 3.

The body structure is composed of a pair of opposed semi-spherical and air-tight concavities 10, having flexible side walls, adapted to crush, to the end that air may be expelled from the cavity so that the cup will be held by suction to a body. The concavities 10 are joined by a center portion 12.

The center portion 12 is provided with a passage establishing communication between the cups 10 which will permit the expelling of the air evenly when the concavities 10 are pressed simultaneously between two surfaces, a flexible slotted partition 17 is located in the communicating passage which permits the air to pass gradually from one concavity to the other when both concavities are pressed simultaneously.

It is believed that the construction and advantages of the structure shown may be apparent from the foregoing paragraphs taken in conjunction with the accompanying drawing without further detailed description.

While the preferred embodiment of the invention has been disclosed it is understood that minor changes in the details of construction, combination and arrangement of co-operating parts may be resorted to within the scope of what is claimed without departing from the spirit of the invention.

I claim:

30 A holding device comprising a pair of suction cups, and a central portion connecting the cups together, said central portion having a longitudinal passage therethrough establishing communication between said cups, said passage having an intermediate partition provided with slits to allow air to gradually pass from one cup to the other when the cups are pressed together.

HORACE V. FARMER.
